[57] CLAIM

The ornamental design for a hand propelled swing, as shown and described.

DESCRIPTION

FIG. 1 is a perspective view of a hand propelled swing showing my new design;

FIG. 2 is a front elevation thereof;

FIG. 3 is a rear elevation thereof;

FIG. 4 is a side elevation thereof, the opposite side being a mirror image of the view shown;

FIG. 5 is a top plan view thereof; and,

FIG. 6 is a bottom plan view thereof.
